ELECTRON DISCHARGE DEVICE

Georges Paul Chevigny, Kew Gardens, and Emile Labin, New York, N. Y., assignors to Federal Telephone and Radio Corporation, a corporation of Delaware

Application January 22, 1942, Serial No. 427,728

4 Claims. (Cl. 250—27.5)

1

This invention relates to electron discharge devices and circuits, and more particularly to such apparatus adapted to operate at ultra high frequencies. It has for its object to improve the operating performance, and increase the frequency and the power output at which such devices may be made to operate effectively. A related object is to provide a simple compact construction, by which an efficient operation is obtained.

There have heretofore been provided vacuum tubes having resonant cavity type circuits arranged to establish ultra high frequency resonance. To enable such tubes to operate effectively, the size of the electrodes should be made small in order that a substantial transfer of energy of the ultra high frequency may be made effective over the electrode areas. Furthermore, it is desired that the electrical impedance of the elements coupling the resonant circuits with the tube electrodes should be made small in order to reduce the power loss across them.

In accordance with this invention there is provided a compact symmetrical arrangement of the component parts of the tube and cavity circuits, which reduces the effective size of the electrodes to half their actual size, and thereby permits a high energy output at a very high frequency. A feature is an arrangement of the cavities symmetrically with respect to the central section of the electrodes so that the tube operates as two tubes, one on either side of the central section. Another feature is the arrangement of a coupling capacity within the vacuum of the tube, through which the cavity is coupled with the corresponding tube electrode, thus facilitating the provision of a large coupling capacity.

The invention will be understood from the following detailed description taken in connection with the accompanying drawing, of which

Fig. 1 shows in longitudinal section, a vacuum tube construction embodying the invention;

Fig. 2 shows in section, a modified construction according to the invention; and

Fig. 3 shows a modification of the arrangement shown in Fig. 2.

Fig. 1 shows a device which is in effect a double tube. It comprises a pair of cathodes 10 and 10a, in a well-known form of filaments displaced longitudinally from each other along the longitudinal axis and supported on filament leads 11, 12 and 13. The lead 11 is connected at the filament midpoint, sealed through insulating dish 14, forming part of the wall of the evacuated vessel. There is placed concentrically around the longitudinally

2

spaced cathodes 10 and 10a, a cylindrical grid electrode 15, which may be formed in a well-known manner to act as a control grid, and having end portions 16 and 17 which may be imperforate conducting cylinders. The grid itself may be a helical wire winding or some equivalent construction such as spaced rods. The grid may be supported in a practical manner; and in Fig. 1, it is shown held by the collar 18 around the mid-section, supported by the rigid grid lead 19, which passes through the sealing glass 20 having the annular portion 21, which in turn is sealed to a cylinder 22, which may be of metal, protruding outwardly from the side of the cylindrical anode 23. This anode is placed concentrically around the grid electrode, and may be supported in a practical way such as between end flanges 24 and 25, which are sealed to respective insulating cylinders 26 and 27, ordinarily of glass, forming part of the evacuated vessel wall and extending beyond the respective ends of the anode. This concentric anode construction is fastened to the insulating dish 14 by means of a conducting collar 28, having flanges 29 and 30, which are sealed respectively to cylinder 27 and dish 14.

The tube is closed at the opposite end by the metallic dome-shaped member 31 attached to a conducting collar 32, which is sealed to the glass cylinder 26 by means of flange 33.

30 For the purpose of tuning the anode-grid circuit, there are provided two tank circuits in the form of resonant cavities 34 and 35, in the form of bodies of revolution; coaxially and symmetrically located with respect to the electrodes. Each 35 of these cavities comprises an outer wall, 36 and 36a respectively, flaring and extending concentrically from the ends of the anode, and inner walls 37 and 37a respectively, extending concentrically from the collars 32 and 28 respectively, 40 so that the outer and inner walls of the cavities form concentric lines, as shown. Annular plungers 38 and 38a may be placed in the annular space of each concentric line to tune it. These plungers are preferably made movable endwise as indicated by their handles, so as to afford a tuning adjustment.

For the purpose of coupling the inner walls 37 and 37a with the respective grid ends to form the 50 anode-grid circuits, there are attached to the collars 32 and 28 respectively, conducting cylinders 39 and 39a which extend inwardly and close to the respective cylinders 16 and 17 at the ends of the grid element so that capacity forms between cylinders 16 and 39, and between 17 and

38a, which couples the inner cavity walls with the respective grid ends.

To complete the grid-cathode circuit there is provided a concentric cylinder 41, within the cylindrical wall 37a of the tank. This cylinder 41 is attached to the mid-point lead 11 of the filaments. The walls 41 and 37a are capacitively coupled by a coupling condenser formed by annular disc 42 in contact with cylinder 37a, and an annular disc 43 in contact with cylinder 41. These discs may both be movable in an endwise direction, as indicated, so that the capacity therebetween and the resonance of the grid-filament circuit can be adjusted.

By its symmetrical construction, the device may be made to operate as two tubes, the two parts being divided at the mid-section line 45 between the filaments 10 and 10a. The cathode 10, together with its corresponding half of the grid and anode, and the resonant tank circuit 34, operate as one tube, and the other cathode 10a together with its grid and anode and the tank circuit 35, simultaneously operates as another tube.

The device may be operated in the usual manner, the required filament voltage being connected to filament leads 12 and 13, a suitable control grid voltage to lead 19, and a suitable anode voltage to anode 23. It may be used as an amplifier, or if desired, as an oscillator by providing sufficient feed-back from the anode circuit to the grid-filament circuit in a well-known manner. Such feed-back could be provided, for example, by connecting a concentric line between cavities 34 and 35 if there is not already sufficient coupling between the electrodes within the tube. Energy can be taken from the tube in a well-known manner such as by placing a suitable energy pick-up device within a cavity. Such an arrangement it shown as the conducting loop 46 connected inside cavity 34 and brought out through concentric tubing 47.

Fig. 2 illustrates another form of tube which likewise acts as a double tube although having a cathode built as a single unit 50. This is surrounded by the concentric grid 51 and anode 52 in a similar manner to that illustrated in Fig. 1. It is provided with a single symmetrical tank extending from one end of the tube to another. This is formed by the enveloping conducting wall 53, placed concentrically around the tube and flaring from the terminal collar 54 at one end, and from the metallic tube sealing member 55 at the other end. Coupling capacity between the tank and the grid is provided by means of the metal cylinder 56, which is re-entrantly extended within the cylinder 58 at the end of the grid. As the cylinder 56 forms part of the wall of the evacuated vessel, this coupling capacity between wall 56 and member 58 has the advantage of being within the vacuum. This capacity 56, 58 may be used for facility of construction and assembly; for the grid member 51 may be inserted into the tube from the right, and the circuit from the left end of the grid to the cavity will be completed through the capacity. This arrangement has the advantage of permitting relative movement between member 58 and 56, as when expansion occurs through heating. If convenient, the members 56 and 58 might be connected together directly, if provision be made for taking care of the thermal expansion of the grid.

There is provided a grid-cathode circuit by means of coaxial cylinders 59 and 60, the cylinder 59 being attached to collar 54, and cylinder 60

being attached to the cathode mid-lead at 61. Cylinders 59 and 60 form a coaxial line, and it may be tuned in a manner somewhat similar to that in Fig. 1 by means of the annular discs 62 and 63 located between, and connected respectively with the coaxial line walls 59 and 60. These lines 62 and 63 may be arranged to move endwise by suitable manipulating members 64 and 65, as shown.

In order to supply anode voltage to anode 52, a conducting rod 52a may be attached to the anode and led out through a hole 53b in the cavity wall 53, such that the rod is insulated from wall 53.

Fins 66 for cooling may be built to extend radially from the anode 52. If it is desired to make provision for air cooling, there may be provided air spaces 67 leading into the tank, and through which air may pass over the fins.

In the embodiment of Fig. 2, the operation is like that of a double tube, being very similar to the operation of the embodiment shown in Fig. 1. Although there is only a single cathode in Fig. 2, the effect of the symmetrical construction of the electrodes and tank is to cause the half of the apparatus at the right of the center section 68 to operate as one device, and the other half as another device in parallel, and the end of each tank is effectively at the center section by reason of the symmetrical construction of the elements both concentrically and in a longitudinal direction.

Fig. 3 illustrates a modification of the arrangement shown in Fig. 2, in which a conducting lead 70 is capacitively coupled to the filament midpoint lead 11 by means of a capacity coupling provided by a cylinder 72 attached to the lead 70 and surrounding member 71. To permit lead 70 to be brought outside the tube, the end wall of the tube is formed by the glass dish 73, which is sealed to the metallic section 74 of the wall of the vacuum tube. Member 74 has formed integral with it, a collar 75 to which is attached the cylinder 76 which forms with the end 58 of the grid, a capacity coupling as in the case of Fig. 2. The conducting lead 70 is extended for a distance coaxially beyond the end of the tube, and there is attached to its end, the closed end of a cylinder 77 coaxially positioned with respect to the tube, and extending endwise of it. There is placed concentrically around the cylinder 77 another cylinder 78 attached to the collar 75, so that cylinders 77 and 78 form a coaxial line. There are placed in this line movable discs 79 and 80, similar to discs 62 and 63 in Fig. 2. These discs are movable endwise by their regulating rods so as to tune the line and also form capacity therebetween.

It will be understood that the right end of the tube in Fig. 3 can be made as the right end of the tube in Fig. 2. With this construction, there is provided a tube which not only has a symmetrical anode-grid resonant circuit, but also has symmetrical cathode-grid circuits, each of which is tunable.

The use of cylinders 72 around the filament mid-leads 71, provides sufficient capacity at the ultra high frequencies to make a relatively low impedance coupling from lead 71 to lead 70. It has the advantage of providing simplicity of assembly and allowing for expansion of members 71 and 70 in an endwise direction with respect to each other when heating occurs. If convenient, the rods 70 and 71 might be made a single continuous rod passing through both ends of the tube

If suitable provision be made for taking care of expansion and contraction of the rod during changes of temperature.

As a result of the effective operation being that of two tubes in parallel in the construction shown, the tube electrodes act electrically as though they were only half their real length; and since their effective length is thus reduced it is possible to operate the tube at a correspondingly higher frequency than otherwise, and still obtain a relatively high degree of energy output from the tube. The construction, enabling the anode circuit-grid coupling capacity to be placed within the vacuum of the tube, results in a further increase of output by reducing the voltage loss across this capacity and reducing the tendency toward sparking between the capacity armatures at high voltages, which occurs less readily in vacuum than in air; and this enables the condenser plates to be brought closer together. The resultant increase of capacity has the desired effect of reducing the voltage fall across it.

What is claimed is:

1. An evacuated ultra-high frequency electron discharge device comprising symmetrically mounted cathode, grid and anode electrodes in which the grid surrounds the cathode and the anode surrounds the grid, an envelope surrounding said cathode and grid electrodes, said anode forming part of said envelope, a cylindrical member extending in said envelope and forming a coupling capacity with the grid, and cavity resonator means effectively connected to the anode and said member and symmetrically mounted both coaxially and longitudinally with respect to the electrodes. 25
2. An ultra high frequency electron discharge device comprising an evacuated vessel, a pair of centrally located cathodes within said vessel, a control electrode mounted concentrically around 40

the cathode, an anode mounted concentrically around the control electrode and forming part of the vessel, and a pair of coaxial cavity walls concentrically mounted both coaxially and longitudinally with respect to the electrodes, one of said walls extending through each end of the vessel and connected with the grid through a capacity coupling within the vacuum.

3. An ultra high frequency electron discharge device comprising an evacuated vessel, a centrally located cathode within said vessel, a control electrode concentrically around the cathode, an anode concentrically around the control electrode and forming part of the vessel, a pair of concentric cavity walls, one being connected with one end of the anode and the other with the other end of the anode, said walls extending outside the vessel in the direction of the respective ends of the vessel, and a second pair of concentric cavity walls extending outside the vessel and mounted within the respective ones of the first pair of cavity walls, and means capacitively coupling said cavity walls with the respective ends of the control electrode through capacity members within the vessel. 10
- 15
- 20

4. An electron discharge device adapted for ultra high frequency operation, comprising an evacuated vessel, a cathode and a control grid within the vessel, said cathode being concentrically mounted within the vessel, said grid concentrically surrounding the cathode, and an anode concentrically surrounding the grid and forming part of the wall of the evacuated vessel, a cavity resonator connected to the anode, and a cylinder extending within the vessel and forming a coupling capacity between the grid and the cavity resonator. 30
